HAMMER DRILL

Ernest A. Mori, Pittsburgh, Pa., assignor to Gulf Research & Development Company, Pittsburgh, Pa., a corporation of Delaware

Application May 16, 1957, Serial No. 659,709

7 Claims. (Cl. 121—25)

This invention relates to well drills and in particular relates to a rotary deep well drill having an improved fluid-actuated percussion mechanism.

In the well-drilling art it is known that the addition of a percussive action at the bit increases the drilling rate of a rotary drill particularly in hard formations. A number of rotary percussion drills have been proposed, an example being described and claimed in Topanelian Patent 2,661,928 entitled, Hammer Drill. This drill, however, has certain shortcomings which have been largely eliminated in the present invention.

This invention provides a rotary percussion drill having long trouble-free service life, improved hammer efficiency, and high percussive frequency. These advantages result from a construction which has improved positive valve action, which provides a hydraulic cushion for the valve and the hammer at the top of their respective strokes, and which provides for the hammer to strike directly on the anvil without any intervening mechanical parts which may break or become battered. In the drill of this invention a higher hammer frequency is attained together with more efficient hammer operation and these result in attainment of higher rates of penetration during drilling.

The drill mechanism shown in Topanelian Patent 2,661,928 employs two hammers the lower of which strikes directly on the anvil and the upper of which strikes on top of the lower hammer. While this mechanism provides two hammer blows per cycle of operation it has been found that the energy delivered to the drill bit by the upper hammer is low because of the intervening member and accordingly the desired efficacy of the double blow per cycle is not realized. It has been found more effective to employ a single hammer impacting directly on the bit stem and to increase the operating frequency of this hammer. Such a result is accomplished by the present invention.

Another defect in the prior devices was occasional faulty valve action which resulted in short and ineffective hammer strokes. This has been corrected in the present invention by providing hydraulic valve-clamping areas so that the valve seal is tightly maintained by the hydraulic operating pressure, and released at the proper moment in the operating cycle by hydraulic action initiated by other cooperating members of the mechanism.

The advantages of the drill of this invention are attained by employing a valve above the hammer and by providing the lower end of the valve with an enlargement or head which cooperates with a valve-cylinder structure so as to quickly release and open the valve. The structure is further improved by reducing the sealing surface of the valve so that a high sealing force per unit area is attained and this provides a positive seal against the top of the hammer thereby insuring consistent hammer operation and eliminating short strokes due to faulty valve seal. Further, by providing a hydraulic cushion for the hammer at the top of its stroke the time required to reverse the upward motion of the hammer is materially

2

shortened thereby reducing the operating time cycle. In addition, the valve is provided with a hydraulic cushion at its most open position so as to quickly return it to the closed or starting position, thereby further reducing the time cycle. The resulting hammer frequency is thus increased very materially.

This invention is illustrated in the accompanying drawings forming a part of this specification, and in which

Figure 1 is a longitudinal section taken through the upper portion of a preferred embodiment of the drill;

Figure 2 is a longitudinal section taken through the intermediate portion of the drill of Figure 1;

Figure 3 is a longitudinal section taken through the lower portion of the drill of Figures 1 and 2; and

Figures 4 to 10 are diagrammatic representations illustrating successive phases in the cyclic operation of the drill.

Reference is made to the drawings in which like numerals indicate the same element in the various views and diagrams.

In Figure 1, adapter 1 serves to connect the drill assembly with the drill stem (not shown) by means of conventional drill collar threads. The drill stem has a central passage as is conventional for supplying drilling

fluid to the drill bit and adapter 1 is also provided with a central passage 2 for the purpose of admitting the pressurized drilling fluid into the drill mechanism. A cylindrical upper housing 3 is screwed into adapter 1 by means of threads 4 and a portion 5 of the adapter of reduced diameter extends into the upper housing 3 with an annular clearance 6 between them. The annular clearance 6 is sufficiently large to permit free flow of drilling fluid between the portion 5 and the inside of upper housing 3 and to this end the area of annular clearance 6

should be substantially the same as that of passage 2. Diagonally drilled openings 7 permit drilling fluid to pass from the passage 2 into the annular clearance 6. The lower end of the extension 5 of adapter 1 is bored out as shown to form an inverted cup-like cylinder 55

which accommodates a valve assembly to be more fully described later.

The lower end of the upper housing 3 is threaded and screwed to a member 8 by means of threads 9 shown in the upper part of Figure 2. The member 8 is substantially of the same outside diameter as housing 3, but has a much smaller internal diameter. Member 8 has screwed to its lower end a cylindrical lower housing 10 by means of threads 11. Member 8 thus forms a constriction intermediate the upper housing 3 and the lower housing 10.

The lower end of housing 10 is fastened to a bit-stem guide 13 by means of threads 14 as shown in Figure 3. The bit-stem guide 13 has a hexagonal central opening 15 which may be relieved slightly as at 16. The inside diameter of lower housing 10 has a downward facing shoulder at 12 (Figure 2). An extension 17 at the upper end of the bit-stem guide 13 provides for clamping between it and the shoulder 12 the elements 18, 19, and 20. Member 18 is a split retaining ring made in two semi-circular sections. Member 19 is an annular cylindrical cage having rings 21

and 22 at its lower and upper extremities respectively, and having openings in the form of slots 23 cut in the wall between the rings. The member 20 is an annular spacer ring which has been spirally cut as at 24 in order to provide axial resilience to the spacer ring. By making the extension 17 of the bit stem of appropriate length, the parts

18 and 19 are firmly held in place by axial compression of the member 20.

Slidably disposed in the bit-stem guide 13 is a bit stem 25 that is substantially circular at its lower end and is threaded as at 26 to receive a conventional drill bit in customary manner. The bit stem 25 is provided with a central passage 27 to provide drilling fluid access to the

70

bit. Immediately above the lower portion of the bit stem 25 is a hexagonal portion which forms a sliding fit on the hexagonal internal bore 15 of bit-stem guide 13. The purpose of the hexagonal connection between bit-stem guide 13 and bit stem 25 is to transmit drilling torque to the bit stem and bit when the drill pipe and drill assembly are rotated in conventional manner. It is apparent that while a hexagonal connection between members 13 and 25 is shown in the drawing, other axially-slidable means for providing transmission of torque from the bit-stem guide 13 to the bit stem 25 may be provided, such as a square connection, splines, keyways, etc. The bit stem 25 is reduced in diameter as at 28 above the hexagonal portion 15 and forms a sliding fit in the upper part of bit-stem guide 13. The upper end of the bit stem is still further reduced in diameter in the region 29 and enlarged slightly again at 30 to a diameter no larger than its diameter at 28. The retaining ring 18 makes a sliding fit around the reduced diameter 29, and the shoulder 31 thus prevents the bit stem from dropping out of the assembly after it is made up.

It is apparent that when the drill mechanism is suspended, the bit stem 25 will drop and will be supported by the shoulder 31 resting on the upper surface of retaining ring 18. When the drill is set on the bottom of the hole, the bit stem 25 may slide upward in the bit-stem guide 13 to occupy the position shown in Figure 3. Fluid in the annular space between the bit stem and the bit-stem guide may escape through the clearance in the sliding fit and the cuts in the split retaining ring 18. Dimensions of the various parts 13, 18, and 25 are so arranged that when the drill is set on bottom, weight is transferred from the bottom of the bit-stem guide 13 to the shoulder 32 of the bit stem 25 whereby weight is applied to the drill bit.

Inside the housing and above the bit stem there is disposed a hammer 33, the lower end of whose body portion is shown at the top of Figure 3. The body of hammer 33 is generally annular in shape and has a central passageway 34 which is in register with the passage 27 of the bit stem. The hammer 33 is enlarged slightly in diameter at 35 and this portion of the hammer body slides freely on the lands of the inside surface of cage 19. The open slots 23 in the cage permit fluid to by-pass the region of enlarged diameter 35, the lands of the cage at the same time contacting the hammer portion 35 thereby guiding the hammer in the mechanism. The body of hammer 33 is of considerable length as shown in Figure 2 and has at its upper end a neck 36 which forms a sliding fit on the inside of member 8. A compression spring 37 is disposed between the bottom of member 8 and a shoulder 38 on hammer 33. The upper end of the neck 36 is threaded at 39 and has screwed thereto a head 40 which also has a central opening 41 in register with the opening 57 in the neck 36. The head 40 after being tightly screwed on the top of hammer 33 may be locked in place by means of a pin or weld (not shown).

The longitudinal dimensions of the hammer assembly are such that it will have considerable vertical movement when the drill mechanism is resting on bottom as shown in Figure 3. In its lowermost position the hammer 33 rests on the top of bit stem 25. The upper limit of its travel occurs when the shoulder 42 of the hammer is substantially opposite the lower edge 43 of the ring 22 of cage 19. At this point in the upward travel of the hammer, fluid becomes trapped in the annular space around the hammer below the member 8 and above the lower edge 43 of ring 22, and this forms a hydraulic cushion at the upper extremity of hammer motion.

Above the hammer there is disposed a valve mechanism as shown in Figure 1, comprising valve body 44 having a longitudinal passage 45 which is in register with the longitudinal passage of the hammer assembly. The passage 45 is countersunk at 46 so that when the valve element 44 rests on top of the hammer there is a relatively

small annular area of contact at 47. The body of valve 44 has a diameter that is larger than the diameter of the hammer neck 36, and the countersink 46 intersects the bottom surface of the valve at a diameter that is not smaller than the diameter of the body of valve 44. The valve body 44 has an outside diameter that forms a sliding fit in a wear ring 49 which is pressed into a counterbore at the lower end of cylinder 55. The internal diameter of the wear ring is smaller than the internal diameter of the cylinder, so that after the wear ring is pressed into the cylinder, the upper part of the wear ring forms an internal projection into the cylinder. The valve 44 has a head 48 at its lower end and the wear ring 49 is counterbored at 50 to an internal diameter that is a sliding fit on the head 48 of valve 44. The valve element 44 will in its lowermost position rest on top of the hammer at 47 and in its upward travel the shoulder 51 enters the lower end of the counterbore 50. The outer cylindrical surface of the valve 44 has a plurality of grooves 52 cut therein, but the grooves 52 do not reach the shoulder 51. The grooves 52 form by-pass channels whose purpose is to permit drilling fluid trapped above the shoulder 51 in the region 50 access to the cylinder space above the wear ring 49, so that the head 48 of valve 44 can enter the counterbore 50. Near the upper end of the valve 44 there are provided a number of openings 53 from the outer surface of the valve to its central channel 45. The upper end of the valve 44 has a shoulder 54 which accommodates a compression spring 56 disposed between the shoulder 54 and the closed end of the cylinder 55.

The longitudinal dimensions of the valve assembly 44 and the wear ring 49 are such that when the drill is suspended off bottom and the shoulder 31 (Figure 3) of the bit stem rests against the top of the ring 18, and the hammer rests on top of the bit stem, and the valve 44 rests on top of the hammer, the passageways 53 are just below the bottom of the internal projection of wear ring 49. In this position drilling fluid enters through the passage 2, holes 7, annular space 6, counterbore 50, holes 53, passage 45, passage 57, passage 34, passage 27 and thence to the drill bit, so that circulation of drilling fluid may be established while running the drill into the hole without operating the drill mechanism. When the drill is set on bottom and brought into the position shown in Figures 1, 2 and 3, the holes 53 are no longer in communication with the annular space 6, whereupon the drill mechanism is caused to operate as will be described later. The grooves 52 are so arranged that their upper end passes the upper end of wear ring 49 as the shoulder 51 enters the counterbore 50. Due to the bypassing effect of the grooves 52, the head 48 of the valve may enter the counterbore 50 until the bottom of the grooves 52 reaches the top of the counterbore 50, after which fluid trapped in the counterbore acts as a hydraulic cushion and terminates upward motion of the valve 44. The longitudinal spacing of the hammer and valve assemblies is such that the hammer reaches its upper hydraulic cushion stop (when shoulder 42 reaches the lower edge 43 of ring 22) just after the valve-head shoulder 51 has entered the counterbore 50.

Operation of the mechanism will be more clearly understood by reference to the diagrams of Figures 4-10 showing diagrammatically the various phases during the operating cycle of the drill mechanism. In the diagrams the numerals indicate the same elements as in Figures 1-3 described above. Figure 4 shows the drill mechanism in the off-bottom or rotating-in position. The bit stem 25 is in its lowermost position and the by-pass holes 53 allow drilling fluid to pass from the annular space 6 to the central passages of the various parts thence to the drill bit at the lower end of the bit stem as previously described. Figure 5 shows the arrangement (also shown in Figures 1-3) when the drill is on bottom and about to begin a cycle of hammer opera-

tion. The holes 53 have now been cut off and the pressurized drilling fluid will raise the hammer and valve. Inasmuch as drilling fluid is now trapped and cannot pass between the valve and the hammer, the resulting pressure build-up raises the hammer and valve as shown in Figure 6. The lifting force is the effective pressure differential times the difference in cross-sectional area between the valve body 44 and the neck 36. This force acts on the bottom annular shoulder of the head 40 and lifts the hammer and valve against the force of gravity and compression of the respective springs. At the same time there is a clamping force holding the valve head 48 against the top of the hammer (at the surface 47 in Figure 2) equal to the effective pressure differential times the difference in cross-sectional area between the valve body 44 and the outside diameter of the top of hammer head 40. As this clamping force is applied over a restricted area 47 it will effect a good seal at all times. Figure 7 shows the valve head 48 entering the counterbore 50 of the cylinder 55, and as the valve head enters the cylinder 55 an additional upward force acts on the valve 44, namely on lower surface of the valve head that is beyond (outside) the outside diameter of part 40. This additional upward force tends to accelerate the valve upward and as a consequence the seal at 47 is quickly broken. Figure 8 shows the hammer in its uppermost position but the valve has continued to move upward to break the seal. As soon as the hammer reaches its uppermost position as shown in Figure 8, which occurs when shoulder 42 (Figure 2) is opposite the edge 43 of ring 22, upward motion of the hammer is arrested. At this point the hydraulic cushion reverses the upward motion of the hammer and it begins to fall until it strikes a percussive blow on the bit stem as shown in Figure 9. The valve, of course, immediately also falls, since as soon as the seal 47 is broken there is no longer any lifting force on the valve. When the falling valve contacts the top of the hammer as shown in Figure 10, the cycle starts over again, Figure 10 being the same as Figure 5.

The above-described mode of operation of the mechanism requires that the outside diameter of hammer neck 36 (i. e. the opening in constriction 8) shall be smaller than the outside diameter of the valve body 44 (i. e. the opening in the upper portion of wear sleeve 49). The difference between these areas should be sufficient so that the upward force developed under pressure will lift the hammer and valve against their gravitational weight and against the compression of springs 37 and 56. Also the clamping force holding the valve and hammer in engagement is dependent on the difference in cross-sectional area of the valve body 44 and the outside diameter of hammer head 40. The countersink 46 in the central passage 45 of the valve should be such that the clamping force acts on a restricted annular area 47 to provide a high force per unit area and thus effect a good seal. The narrow annular sealing area 47 minimizes the opportunity of chips lodging at this point and the high concentration of clamping force will tend to dislodge or crush any chips which may happen to be there and whose presence could cause the valve seal to leak.

The mechanism in its preferred form employs the springs 37 and 56 to assist in the downward acceleration of the hammer and valve respectively, but the mechanism may be operated without these springs but at a lower hammer frequency. Also it is not essential that the hammer and the valve be provided with hydraulic cushions as described, but such cushions raise the hammer frequency by shortening the reversing time of these elements.

In order to insure against any possibility of the mechanism jamming in the uppermost position of the hammer, an annular shoulder 58 (Figure 2) is provided on the hammer neck 36. The shoulder 58 acts as a mechanical stop and contacts the bottom of member 8 to arrest the

upward motion of the hammer in the event that the previously-mentioned hydraulic cushion should fail to stop the hammer due to wear or other reason. The shoulder 58 is longitudinally so positioned that it stops upward travel of the hammer (in the event of failure of the hydraulic cushion to do so earlier in the cycle) before the valve reaches its upward limit. This prevents the mechanism from becoming hydraulically locked. Such a mechanical stop is however not essential to operation of the device.

What I claim as my invention is:

1. In a fluid-operated well-drilling mechanism of the type comprising a tubular housing, an inverted cup-like cylinder longitudinally mounted in said housing, an internal constriction in said housing below said cylinder, means affording pressurized fluid access to the interior of said housing between said cylinder and said constriction, a bit stem slidably disposed in said housing below said constriction, an elongate hammer in said housing slidably sealed against said constriction and having a longitudinal passage, and a valving element above said hammer having a body portion of larger outside diameter than the inside diameter of said constriction and having a longitudinal passage in register with said hammer passage, the body portion of said valving element being slidably sealed against an internal surface of said cylinder, the improvement which comprises an annular internal projection in said cylinder intermediate the closed end and the rim of said cylinder, the body of said valving element being slidably sealed against said projection, an annular head on the lower end of said valving element, and said head forming a sliding fit in said cylinder below said projection.
2. In a fluid-operated well-drilling mechanism of the type comprising a tubular housing, an inverted cup-like cylinder longitudinally mounted in said housing, an internal constriction in said housing below said cylinder, means affording pressurized fluid access to the interior of said housing between said cylinder and said constriction, a bit stem slidably disposed in said housing below said constriction, an elongate hammer in said housing slidably sealed against said constriction and having a longitudinal passage, and a valving element above said hammer having a body portion of larger outside diameter than the inside diameter of said constriction and having a longitudinal passage in register with said hammer passage, the body portion of said valving element being slidably sealed against an internal surface of said cylinder, the improvement which comprises an annular internal projection in said cylinder intermediate the closed end and the rim of said cylinder, the body of said valving element being slidably sealed against said projection, an annular head on the lower end of said valving element forming a sliding fit in said cylinder below said projection, a by-pass channel in said valving element adapted to permit fluid to by-pass said projection when the head of said valving element enters the lower end of said cylinder.
3. In a fluid-operated well-drilling mechanism of the type comprising a tubular housing, an inverted cup-like cylinder longitudinally mounted in said housing, an internal constriction in said housing below said cylinder, means affording pressurized fluid access to the interior of said housing between said cylinder and said constriction, a bit stem slidably disposed in said housing below said constriction, an elongate hammer in said housing slidably sealed against said constriction and having a longitudinal passage, and a valving element above said hammer having a body portion of larger outside diameter than the inside diameter of said constriction and having a longitudinal passage in register with said hammer passage, the body portion of said valving element being slidably sealed against an internal surface of said cylinder, the improvement which comprises an annular internal projection in said cylinder intermediate the closed end and the rim of said cylinder, the body of said valving element being slidably sealed against said projection, an annular head on the lower end of said valving element forming a sliding fit in said cylinder below said projection, a by-pass channel in said valving element adapted to permit fluid to by-pass said projection when the head of said valving element enters the lower end of said cylinder.

and the rim of said cylinder, the body of said valving element being slidably sealed against said projection, an annular head on the lower end of said valving element forming a sliding fit in said cylinder below said projection, a by-pass channel in said valving element adapted to permit fluid to by-pass said projection when the head of said valving element enters the lower end of said cylinder, and said by-pass channel being cut off by said projection before the head of said valving element reaches said projection.

4. In a fluid-operated well-drilling mechanism of the type comprising a tubular housing, an inverted cup-like cylinder longitudinally mounted in said housing, an internal constriction in said housing below said cylinder, means affording pressurized fluid access to the interior of said housing between said cylinder and said constriction, a bit stem slidably disposed in said housing below said constriction, an elongate hammer in said housing slidably sealed against said constriction and having a longitudinal passage, and a valving element above said hammer having a body portion of larger outside diameter than the inside diameter of said constriction and having a longitudinal passage in register with said hammer passage, the body portion of said valving element being slidably sealed against an internal surface of said cylinder, the improvement which comprises an annular head on the upper end of said hammer, an annular head on the lower end of said valving element, and the lower end of the longitudinal passage of said valving element having a diameter larger than the outside diameter of the body of said valving element.

5. In a fluid-operated well-drilling mechanism of the type comprising a tubular housing, an inverted cup-like cylinder longitudinally mounted in said housing, an internal constriction in said housing below said cylinder, means affording pressurized fluid access to the interior of said housing between said cylinder and said constriction, a bit stem slidably disposed in said housing below said constriction, an elongate hammer in said housing slidably sealed against said constriction and having a longitudinal passage, and a valving element above said hammer having a body portion of larger outside diameter than the inside diameter of said constriction and having a longitudinal passage in register with said hammer passage, the body portion of said valving element being slidably sealed against an internal surface of said cylinder, the improvement which comprises a neck of reduced diameter intermediate an upper head portion and a lower body portion of said hammer, said neck forming a sliding seal against said constriction, and means sealed to said housing intermediate said bit stem and said constriction forming a sliding seal against the body of said hammer when said hammer is proximate its uppermost position.

6. In a fluid-operated well-drilling mechanism of the type comprising a tubular housing, an inverted cup-like cylinder longitudinally mounted in said housing, an internal constriction in said housing below said cylinder, means affording pressurized fluid access to the interior of said housing between said cylinder and said constriction, a bit stem slidably disposed in said housing below said constriction, an elongate hammer in said housing slidably sealed against said constriction and having a

longitudinal passage, and a valving element above said hammer having a body portion of larger outside diameter than the inside diameter of said constriction and having a longitudinal passage in register with said hammer passage, the body portion of said valving element being slidably sealed against an internal surface of said cylinder, the improvement which comprises a neck of reduced diameter intermediate an upper head portion and a lower body portion of said hammer, said neck forming a sliding seal against said constriction, a generally-tubular cage held in said housing coaxially therewith, said cage having a continuous ring fitting tightly in said housing and located between the top of said bit stem and the bottom of said constriction, said cage having below said ring a slotted body portion permitting unobstructed longitudinal motion of said bit stem and said hammer body, and the inside surface of said ring forming a sliding seal against the outside surface of said hammer body when said hammer is proximate its uppermost position.

20 7. In a fluid-operated well-drilling mechanism of the type comprising a tubular housing, an inverted cup-like cylinder longitudinally mounted in said housing, an internal constriction in said housing below said cylinder, means affording pressurized fluid access to the interior
25 of said housing between said cylinder and said constriction, a bit stem slidably disposed in said housing below said constriction, an elongate hammer in said housing slidably sealed against said constriction and having a longitudinal passage, and a valving element above said
30 hammer having a body portion of larger outside diameter than the inside diameter of said constriction and having a longitudinal passage in register with said hammer passage, the body portion of said valving element being slidably sealed against an internal surface of said cylinder,
35 the improvement which comprises an annular internal projection in said cylinder intermediate the closed end and the rim of said cylinder, the body of said valving element being slidably sealed against said projection, an annular head on the lower end of said valving element,
40 said head forming a sliding fit in said cylinder below said projection, the lower end of the longitudinal passage of said valving element having a diameter larger than the outside diameter of the body of said valving element, a neck of reduced diameter intermediate an upper head portion and a lower body portion of said hammer, said neck forming a sliding seal against said constriction, a generally-tubular cage held in said housing coaxially therewith, said cage having a continuous ring fitting tightly in said housing and located between the top of
45 said bit stem and the bottom of said constriction, said cage having below said ring a slotted body portion permitting unobstructed longitudinal motion of said bit stem and said hammer body, and the inside surface of said ring forming a sliding seal against the outside surface of said hammer body when said hammer is elevated its maximum extent.
